UNITED STATES PATENT OFFICE.

GUSTAV FERDINAND JULIUS ECKERS, OF HAMBURG, GERMANY.

CONTAINER FOR FLUID.

Application filed January 25, 1927, Serial No. 169,472, and in Germany February 9, 1926.

Containers in which the depth of the fluid is automatically controlled are known. The known constructional forms provide within a main container or beside a main container in conjunction therewith an accessory receptacle. The fluid is allowed to flow through an opening extending on the bottom of the container into the receptacle in the same proportion as the air may enter the said opening. All those containers are not used in the practice due to the expensive production and the difficulty of charging and recharging them with the fluid and due to their being easily breakable.

The present invention relates to a container of utmost simple construction which removes all drawbacks above referred to, and provides a double closure in connection with bottles, flasks and vessels of any desired shape adapted to receive glue, ink, color or the like.

Reference is made to the accompanying drawing in which a constructional form of the invention is shown by way of example.

The container *a* preferably made of press-glass has a somewhat conically formed neck *d*. A glass tube *b* is arranged in the container *a*. The neck of the glass tube may also be shaped somewhat conically and may be detachably secured to the neck *d* in a fluid and air tight manner for instance by any adhesive means.

It is obvious that instead of using adhesive means it is also possible to connect the neck of the tube tightly with the neck *d* by providing annular pieces of cork, rubber or the like, more particularly, if the diameter of the neck of the tube is not fully adapted to the diameter of the container's neck *d*. A closure device comprising the parts *c*, *f* and *g* is located in the tube *b* independently arranged thereof. *c* is a ring, the part *f* extends from the ring *c* to the packing plate *g*.

The packing plate *g* may be constructed of rubber or any other elastic or easily formable material and is suitably made of a larger diameter than the lower end of the glass tube, so that in spite of the rubber plate being somewhat downwardly deflected when put into position it may yet fit close to the walls of the tube *b* and ensure an absolutely fluid-tight closure.

The manner of operation is as follows: The container *a* into which the tube *b* is not yet arranged is charged in the ordinary manner with the desired liquid, for example glue, however not up to the full height. After the tube *b* has been provided with the rubber

plate *g* which has to fit fluidtight within the lower end *h* of the tube *b* the latter one is introduced into the container *a* not completely filled, the air escapes at *d* and the fluid is rising in the container in the same proportion as the volume of the tube *b* occupies space. As the volume of the tube remains always the same, it is possible to mark the container at a predetermined place up to which the container must be charged in order to be almost fully filled up after the tube has been introduced. If the neck of the tube lies close to the neck of the container the air-tight connection is effected by adhesive which may be readily dissolvable if desired. If there is a distance between the neck of the tube and the container's neck a packing ring or the like made of rubber or similar material is inserted. The whole device may then be closed at *d* by a cover portion *k* adapted to the conical form of the container and suitably made of a material which is readily drying up. The part *k* may then be covered by a mark, label or trade mark of the respective manufacturing firm. The container can therefore only be opened after the closure *k* with the trade mark has been destroyed. By this manner the genuineness of the contents may be warranted.

The present invention offers the following remarkable advantages:

The manufacture of the container *a* is very simple and inexpensive, and yet the container may be stable and durable. The inner tube-like part *b* may be constructed of quite thin and cheap glass as it is not subjected to damages from outside, and may be adapted to any desired container by inserting corresponding corks or rubber rings or the like. The parts *g*, *f* and *c* forming a unit may also be produced in the simplest and most inexpensive manner, the part *g* being made in such a manner as to ensure an absolutely tight closure at about the level of the constant depth of the liquid so that while in transport the contents will not in any position of the container enter the tube *b*. The closure *k* may warrant the genuineness of the contents. After the vessel has been emptied it is only necessary to put it into warm water, which will allow the neck of the tube *b* to be removed from the part *d* of the container *a* by dissolving the adhesive. If the tight connection has been effected by annular packing members made of cork, rubber, or the like the tube

may be removed of course without any treatment in warm water. The container is then recharged in the ordinary manner and made ready for transport.

5 The novelty of the present invention consists in that a container with constant depth of the fluid is provided with a double closure so that when in transport the contents are prevented from being spilled and of entering the 10 tube; furthermore the second closure portion is adapted to give a guarantee for the genuineness of the product. It is of great importance that according to the present application an air- and fluid-tight closure is effected 15 at *d* so that on taking out the part *g* from the tube *b*, the tube will not be removed from the container *a*. It is therefore necessary when using packing members made of rubber or cork to arrange them more close than 20 the part *g* in the lower end of the tube *b*.

It is obvious that constructional or other changes may be introduced without departing from the scope of the present invention.

Having now particularly described and ascertained the nature of my said invention and in what manner the same is to be performed, I declare that what I claim is:

1. A container for fluid with automatically controlled uniform level of fluid, including a 25 main container, a tube-like part having a 30 conically shaped neck and being detachably arranged in said container and fitted air tight

therewith by means of adhesive, said part having an upper opening and a lower opening approximately reaching the bottom of 35 the main container.

2. A container for fluid as claimed in claim 1 in which said tube-like part is fitted air tight with the container by means of packing members. 40

3. A container for fluid as claimed in claim 1 including a closure portion arranged at the lower end of said tube-like part at about the level of the depth of the fluid, said closure portion being provided with means permitting withdrawal of the closure portion. 45

4. A container as claimed in claim 1 comprising a closure member provided on the neck of the container and unremovable without destruction. 50

5. A container for fluid with automatically controlled uniform depth of fluid, including a main container having a tube-like part detachably arranged therein and fitted air-tight thereto, said part having an upper and a 55 lower opening approximately reaching the bottom of said container, a closure member arranged at the lower end of said tube-like part at approximately the depth of the fluid, means permitting the removal of the closure portion, and a closure member fitted on the neck of the main container. 60

In testimony whereof I affix my signature.
GUSTAV FERDINAND JULIUS ECKERS.
